SEMI-FROZEN PRODUCT DISPENSER, OR SIMILAR ARTICLE

Robert B. Hartley, Columbia Heights, Minn., assignor to
The Cornelius Company, Anoka, Minn.

Filed Nov. 9, 1970, Ser. No. 25,900

Term of patent 14 years

Int. Cl. D15—08

U.S. Cl. D94—3

FIG. 2

FIG. 1 is a front perspective view of a semi-frozen product dispenser, or similar article, showing my new design, the opposite side being a mirror image of the side shown; and

FIG. 2 is a top plan view thereof on a reduced scale.
I claim:

The ornamental design for a semi-frozen product dispenser, or similar article, substantially as shown and described.
